ADJUSTABLE SCARIFIER TOOTH

Joseph R. Godfrey, Concrete, Wash.

Application April 20, 1938, Serial No. 203,145

2 Claims. (Cl. 262—8)

The present invention relates to an adjustable scarifier tooth and embodies means for locking the tooth in vertically adjusted position in its supporting frame.

More specifically, the present invention embodies a scarifying tooth having means adjacent its inner end for adjustably supporting the tooth in vertically adjusted position, said adjustable supporting means embodying a pin adapted for positioning adjacent the upper end of the supporting brackets when the tooth is initially positioned therein and after the tooth has become worn and reduced in length, to support the pin at a point adjacent the lower end of the bracket.

A further object is to provide an adjustable scarifying tooth and supporting bracket of substantially simple construction, which is strong and durable, which enables the convenient adjustment of the tooth when desired, and which at the same time is relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which—

Figure 1 is a side elevational view of the supporting bracket showing the teeth supported adjacent the upper portion thereof, and with parts broken away and shown in section.

Figure 2 is a similar view showing the tooth supported in the lower position in the bracket, and with parts broken away and shown in section, and

Figure 3 is a transverse sectional view.

Referring now to the drawing in detail, the numeral 5 designates a portion of the frame of a scarifier within which the supporting tooth block or bracket 6 is suitably secured, the front edge of said bracket having a V-shaped groove 7 extending longitudinally thereof and within which the V-shaped tooth 8 is seated, the lower edge of the tooth 9 projecting below the lower edge of the bracket 6 as clearly illustrated in Figures 1 and 2 of the drawing.

The upper rear edge of the tooth 9 is formed with vertically spaced half-round notches 10 and the bracket 6, adjacent its upper edge is provided with an opening 11 for receiving a transversely extending pin 12 adapted to selectively seat in the notches 10 of the tooth. The pin 12 is retained in position by a cotter key 13 or the like.

The notches 10 are formed in the tooth adjacent only its upper end and accordingly when the tooth has become worn and reduced to a length less than the length of the supporting bracket 6, the pin 12 is removed from the opening 11 in the upper end of the bracket and positioned in an opening 14 which extends through the opposite sides of a substantially U-shaped guide 15 secured adjacent the lower portion of the bracket by a rivet 16. The opening 14 also extends through the bracket 6 for receiving the pin 12 to engage one of the notches 10 of the tooth when the latter is positioned in the lower end of the bracket in the manner shown in Figure 2.

In this manner the tooth may be adjusted until the same has become worn to a relatively short size and without requiring the formation of the notches 10 throughout the entire length of the tooth. The opening 14 in the opposite sides of the guide 15 serve to reinforce the lower opening in the bracket to prevent wear caused by pressure of the tooth on the pin 12.

It is believed the details of construction and manner of use of the device will be readily understood from the foregoing without further detailed explanation.

Having thus described the invention, what I claim is:

1. In an adjustable scarifier tooth, a supporting bracket arranged in upright position, a groove in one edge thereof, a scarifier tooth seated in said groove, said bracket having a plurality of vertically spaced openings, a guide secured to the bracket and bridging the groove for retaining the tooth therein, vertically spaced notches in one edge of the tooth and a pin removably inserted in said openings and engaging one of the notches to secure the tooth in vertically adjusted position.

2. In a scarifier tooth support, a vertical bracket having a vertical groove in one edge, a guide adjacent the lower portion of the bracket, said bracket having an opening adjacent its upper end and also having an opening adjacent its lower portion, said guide having an opening registering with said last named opening in the bracket, all of said openings intersecting the groove, a scarifier tooth positioned in said groove, notches in the upper portion of the tooth and a pin selectively positioned in said openings and engageable in said notches for securing the tooth in vertically adjusted position in the bracket.

JOSEPH R. GODFREY.
